LIGHT SHADE

Paul Ceasar, Brooklyn, N. Y., assignor of one-third to Maurice Finkelstein and one-third to Samuel Seligman, both of New York, N. Y.

Application March 11, 1933, Serial No. 660,370

4 Claims. (Cl. 240—105)

The present improvements relate in general to lamp shades and reflectors, and more particularly to reflectors having improved details of construction adapted for use with incandescent bulbs.

5 A primary object of the invention is to provide new and useful improvements in reflectors which are light and durable, and may be economically manufactured. A further object is to provide a reflector which may be stamped and 10 produced from a blank in one operation.

Another object is to provide an improved one-piece shade or reflector which may be readily and easily mounted in operative position. A still further object is to provide a reflector having an 15 integral collar for locating the device in proper position when mounted, and at the same time provide for air circulation about the bulb.

Other objects include the provision of novel 20 means for automatically adjusting and centering the lamp with respect to the shade or reflector. Further objects will be apparent to those skilled in the art upon reference to the accompanying specification and drawing, in which.

Fig. 1 is a side elevation of one form of the 25 present improvements associated with a lamp socket;

Fig. 2 is a plan view of the blank from which the reflector is provided;

Fig. 3 is a section on line 3—3 of Fig. 1; 30

Fig. 4 is a vertical section of the reflector, with the lamp and socket illustrated in dot and dash lines;

Fig. 5 is a side elevation of the underside of 35 the shade associated with a bulb.

Referring to the drawing, the completed shade or reflector 5 is illustrated in Fig. 1 in association with the socket 6 and lamp or bulb 7.

The shade 5 is preferably made from sheet 40 metal having a lustre so that the device may serve both as a shield and as a reflector. In the preferred method of manufacture blanks 5, such as illustrated in Fig. 2, are stamped from the sheet metal. They may be of any size suitable for the particular bulb with which they are to be used.

45 As the next step in the formation of the improved shade, the flange 8 is folded back in a direction toward the body of the blank. This folding operation is performed on the blank while it is flat, so that the subsequent bending operation may be imposed on the blank when folded.

The blank with the flange 8 folded thereunder, is now bent about a matrix or die, with the flange on the inside. The die and folding operation is such that the shade or reflector is open at both 50 ends. The outline of the blank is such that when

the blank is bent along its longitudinal axis, the end of the blank having the flange 8 provides a relatively narrow neck portion which is defined by collar 8.

5 The body of the shade 5, as illustrated, flares outwardly from its union with the collar to its outer extremity which is preferably designed to extend to or beyond the tip of the bulb 7. This flared outer end of the shade facilitates insertion and removal of the bulb and permits illumination in that direction.

Upon reference to Fig. 5, it is seen that the shape of the blank, and the folding operation imposed upon it, causes the completed shade 5 to have a side opening 10 which increases in size 10 from the region of the collar 8. The walls 11 defining this opening, partly encompass the bulb, but recede as the outer end of the shade is approached, so that the greater portion of the rounded end of the bulb is not shielded on that side which has the opening 10. When associated with the bulb therefore, the illumination is downwardly and outwardly, although the walls 11 serve as shades at the sides and bottom.

At any convenient stage in the course of manufacture, but preferably after flange 8 has been folded over, the ends of the blank may be bent 15 to provide ears 12, whereupon they may be suitably punched for accommodating the screw 13 and wing nut 14.

In assembling the shade about the socket and lamp, the screw 13 is removed, and the shade, being resilient, may be sprung about the shank of the socket, whereupon the screw may be put through ears 12 and the wing nut 14 tightened. The completed shade, ready for use, has openings 20 at the side and ends substantially as shown in Figs. 3 and 5, so that it is necessary to force the walls apart, as the shade is snapped over the socket. However, the shade resists this movement and springs back to original position. If a bulb 25 is not in place in the socket, the shade may be applied and removed longitudinally of the socket.

As illustrated, the collar 8 supplemented by the main body of the shade exerts a spring grip on the shank of the socket, whereupon it is held in 30 position with the aid of the screw. This spring grip tends to resist removal of the shade, thereby serving to hold the same in position.

35 The relation of collar 8 to the socket and lamp is such that the shade 5 is maintained in spaced relation with respect to the bulb 7 on all sides thereof. This is apparent upon inspection of the drawing, wherein collar 8 makes a snug fit with the socket, and the axis of the collar, if produced, 40

would substantially pass through the outer center of the bulb end. This relation of parts, coupled with the annular V-shaped space provided between collar 8 and shade 5, insures a substantial clearance between the bulb and shade. This provides an air circulation pocket at all times for insulation purposes whereby the heat of the lamp is not transmitted to the shade, and the latter is therefore maintained relatively cool. It will be observed that the ends of the collar 8 adjacent ears 12, have the same curvature as the main portion of the collar. This provision insures the proper spacing of the portions 11 from the bulb, in the same manner as the remainder of the shade.

By providing the collar 8 integral with and closely associated with the shade or reflector, the device readily adjusts itself in proper position about the socket 6. Furthermore, the improved collar and manner of associating same with the shade, permits the collar to center the bulb with respect to the shade, as previously pointed out.

In providing an enlarged open end in the reflector or shade 5, increased diffusion of light is afforded and at the same time, the bulb may be replaced with ease. Likewise, bulbs of varied sizes may be employed, since the enlarged end presents no limitation on the length of the bulb.

The present improvements may be very economically manufactured in quantities by simply stamping out the blank, folding and then bending same. This is accomplished by few operations at a minimum expenditure of labor. Accordingly, a light, strong and durable shade may be inexpensively made which will be accurate in contour, and suitable, without modification, for immediate use with a bulb and socket.

A further marked advantage of the present improvements resides in the fact that neither the surface nor the texture of the metal blank is impaired. This is due to the fact that it is unnecessary to stretch the metal which frequently breaks, mars or scratches in methods requiring stretching, thereby impairing the lustre and surface. Such undesirable results are eliminated in the shade of the present improvements.

It is significant that the body 5 of the shade

extends about the greater portion of the socket 6, so that the perforations in the body may be aligned for accommodating the rigid securing means which describes a chord across the circular end of the shade. In the illustrated embodiment, the screw 13 extends through opposite sides of the shade and through opposite ends of the collar 8. However, it is manifest that said screw or other securing means may seize and hold only the sides of the shade and not the ends of the collar, or the arrangement may be the converse.

Various modifications within the scope of the present improvements may occur to those skilled in the art, without departing from the purview of the invention.

I claim:

1. A lamp shade for incandescent bulbs formed from sheet metal comprising a blank having a narrow strip at one transverse end folded back substantially upon the body of the blank, said blank thereupon being bent along its longitudinal axis to provide a tubular shade of varying cross section from one end to the other, and a securing member for holding the blank in operative position about a lamp.

2. A sheet metal blank comprising a body portion defining a tubular shade which is relatively narrow at one end and flaring in increasing cross section to the other and larger open end, a collar portion integral with said body portion, said collar portion being folded within said tubular body portion and defining a substantially circular band from which said tubular body portion is spaced.

3. A lamp shade for incandescent bulbs comprising a shade portion and an integral collar for aligning the bulb, means defining perforations in opposed portions of said shade portion and a member extending therethrough for securing the shade in position.

4. A lamp shade for incandescent bulbs comprising a shade portion and an integral collar for aligning the bulb, means defining perforations in opposed portions of said shade portion and collar, and securing means extending through said shade and collar.

PAUL CEASAR.
